UNITED STATES PATENT OFFICE.

FRANK P. HERRICK, OF NEW YORK, N. Y.

DESIGN FOR AN EYE.

SPECIFICATION forming part of Design No. 32,465, dated April 10, 1900.

Application filed November 2, 1899. Serial No. 735,638. Term of patent 14 years.

To all whom it may concern:

Be it known that I, FRANK P. HERRICK, a citizen of the United States, residing at New York, in the county and State of New York, but temporarily domiciled at Puerto Cortez, Spanish Honduras, Central America, have invented and produced a new and original Design for Eyes, of which the following is a specification, reference being had to the accompanying drawing, forming part thereof.

The drawing represents a plan view of an eye, showing my new design.

As shown in the drawing, the eye is formed from a single piece of wire, and the leading feature of my design consists of the lateral

extensions *a a* from the loop *A*, the backward parallel extensions *b b*, the inwardly-directed offsets *c c*, and the parallel prongs *d d* of substantially the same length as the parallel extensions or sides *b b*. 20

Having described my invention, what I claim as new, and desire to secure by Letters Patent, is—

The design for an eye, as herein shown and described.

FRANK P. HERRICK.
